Inventor:

Ernest Hermann Wilhelm von Niessen

By Hugh N. Magner,
his attorney.

UNITED STATES PATENT OFFICE.

ERNST HERMANN WILHELM VON NIESSEN, OF WILMERSDORF-BERLIN, GERMANY.

BRISTLE FOR BROOMS AND BRUSHES.

1,390,973.

Specification of Letters Patent. Patented Sept. 13, 1921.

Application filed October 24, 1919. Serial No. 333,118.

To all whom it may concern:

Be it known that I, ERNST HERMANN WILHELM VON NIESSEN, captain lieutenant, retired, of the former Imperial German Navy, citizen of Germany, residing at Wilmersdorf-Berlin, 25 Brandenburgerstrasse, Prussia, Germany, have invented certain new and useful Improvements in Bristles for Brooms and Brushes, (for which 10 I have filed applications in Germany, dated Oct. 1, 1917, and [addition] Nov. 22, 1917,) of which the following is a specification, reference being had therein to the accompanying drawing.

15 The present invention relates to a novel method of making the bristles for brooms and brushes from bamboo Madagascar, pepper and similar reed. Heretofore such material was obtained from the reed or bamboo 20 by shaving or splitting the same longitudinally, and the bristles thus obtained were secured by means of pitch or the like into the brush-wood or broom-heads, because the 25 easily cause the bristles to break at the point where they have to be sharply bent over the wire. When the bristles are thus secured by means of pitch, they will not remain for long tight in such position, as the 30 sharp edges of the bristles will, under the pressure in sweeping, soon destroy the pitch. The brush material according to the present invention, now, will not require any 35 of the customary means for securing it in the broom head, because it has at one end an enlarged head, owing to the peculiar method of crosswise cutting the reed and 40 subsequently splitting the same, as herein-after described. This head will by itself 45 securely hold the bristles in the broom head or brush-wood. Preferably the individual bristles are also split once or several times, also crosswise in a longitudinal direction from the free end up to close to the said head.

In the accompanying drawing—

Figure 1 shows the way in which the reed or bamboo pole is cut crosswise and subdivided or split longitudinally.

50 Fig. 2 is a perspective view of a bristle thus obtained.

Fig. 3 is another bristle thus obtained, split longitudinally on right angled lines and thereby forming a bundle of bristles.

55 Fig. 4 is a cross-section through the bristle according to Fig. 3.

Fig. 5 is a cross-section through a bristle, which has been several times split longitudinally.

Figs. 6, 7 and 8 show various modes of 60 securing the bristles according to the present invention.

As shown in Fig. 1, the reeds are cut crosswise, preferably by means of a circular or a band-saw, always on the same side of 65 the knots *b* and close to these (see cut A—B). When the distance between two neighboring knots is very large the said cuts may be made in such knots and also intermediary between them. After the reeds have been 70 thus cut crosswise, they are split longitudinally to pieces having the form shown in Fig. 2. These pieces *c* have at the one end an enlarged head *b*. Of course it is also possible to first split the whole length of 75 reed longitudinally into thin strips and then cut these crosswise always on the same side of the knots; but this would be much more troublesome and would neither yield the uniform pieces *c*. The closer the splits are 80 made longitudinally, the thinner the said pieces *c* will be, which, when made from reed with thin walls, may be used as they are for stable or snow brushes and the like. For sweeping streets, and in particular for 85 floors in factories or the like, the bristles must, however, be more elastic. This is obtained by the pieces *c* being split again from their end opposite to the head, longitudinally but not throughout their whole length, 90 and only to close up to the head. Such splitting of the pieces *c* may be done either once only, or several times on right angled lines, or the like, so that eventually the piece *c* 95 consists of a bundle of fine bristles joined together by the head *b*. By such longitudinal splitting of the pieces *c* bristles of any degree of fineness may be produced. This splitting may be performed either by hand or by means of a special machine and is very 100 easily carried out. As the core part of the material will, after some time, break away readily, it may, from the very first be cut away by slicing it off. When the pieces *c* 105 are split once only on right angled lines or in form of a cross, it is advisable to make the cut parallel to the outer side somewhat closer to this side, as the texture of the reed will here more easily allow of such splitting. Besides a cut made closer to the core of the 110 reed will always show the tendency to run toward the center, so that the individual

bristles will become uneven and lead to unnecessary waste.

As the knots are always closer to each other toward the root end, the short pieces 5 of reed bristles obtained therefrom according to the present invention may be used for making brushes, scrubbers and the like. The waste produced in splitting the pieces c longitudinally may be utilized as pot-brushes.

The bristles produced according to the present invention may be secured in various ways into the broom heads or brush-woods. This securing of the bristles does not fall 15 within the scope of the present invention. It may be done, for example, in the manner shown in Fig. 6, where the bristles are introduced with their thin end through holes in the brush-wood from above; when the 20 head b reaches the brush-wood d, it will be stopped there and a suitably recessed cover piece is placed over these heads. Or the bristle-holes may taper downward or be set-off (Figs. 7 and 8) so as to receive the

bristle heads; when several bristles are introduced into the same hole, the heads will bear against each other and support each other in the upper part of the hole. The bristle-heads will, furthermore, cut with their comparatively sharp edges into the 30 wood of the brush-head and thereby prevent their shifting therein. For further preventing the bristle-heads from shifting and eventually falling out from their holes, wooden shoe-pegs may be driven into the 35 empty spaces around them in said holes.

I claim:

A bristle tuft made from a longitudinal section of a joint of a reed, and having at one end an integral portion of the reed knot 40 as a head, and the remainder of the section being split longitudinally.

In testimony whereof I hereunto affix my signature in the presence of two witnesses:

ERNST HERMANN WILHELM von NIESSEN.

Witnesses:

HERMANN TREIBEL,
FRIEDRICH WILHELM Mews.
